Filed Apr. 21, 1967, Ser. No. 6,787

Term of patent 14 years

(Cl. D15—11)

Fig. 3.

FIG. 1 is a view in side elevation of a lounge chair showing our new design;

FIG. 2 is a top plan view thereof;

FIG. 3 is a front elevational view thereof;

FIG. 4 is a bottom view thereof;

FIG. 5 is a rear elevation view thereof; and

FIG. 6 is a side elevational view of a modified form of the lounge chair of FIG. 1 wherein the horizontal slots in the seat and backrest portion have been omitted.

The dominant features of our design reside in those portions shown in full lines on the drawing.

We claim:

The ornamental design for a lounge chair, substantially as shown and described.
